Letters Patent.

The schools referred to in the Library Patent and making part of the same containing a description in the words of the said Mr. Thos. himself of his improvement in the mode of flattening Rocks, Minerals, & &c.

To all to whom these presents shall come,

Be it known, that I, Alonzo Goss, formerly of Annapolis, & Present
of Nova Scotia, now of the City, County & State of New York, a
qualified artist, have invented or discovered a new and useful in-
vention in the art of blasting rocks, Minerals, & Earth, & the following
is a full and exact description of the method of blasting as improved
by me. This invention or discovery consists in the application of
the electric spark to the ignition of the powder in the rock, mineral,
or earth instead of the ordinary priming & train,

The superiority of explosives consists in enabling operators to burst off larger masses of rock &c, by igniting a number of charges of powder at the same instant. The masses or blocks may also be made of more regular proportions than by the common method, & this save much expense, in the hewing of the stone & transportation which gun powder may likewise be saved. These are its smaller advantages. Its great usefulness consists in being adapted to the clearing away of obstructing presented by mountains in the route of emigrant roads & for this purpose may be of invaluable service to a Land Country.

and the coils be wound on a miller in a regular line of sufficient length, then with an ordinary electrical machine & battery, pass one end of the positive conductor to each ring & connect the ends of the coil in series.

fully prepared was the bottom of the first hole in the range of holes to be charged, then to conduct the spark which according to the laws of electricity will be here elicited unto the next charge or part of the charge, another wire bent as above should be cut of the length it is intended to separate the charges or parts of the charge from each other, & inserted in the opposite side of the piece of baked wood above mentioned thus. [ ] & then by bending and inserting the opposite end in another piece of baked wood, the spark is a second time elicited and so on, to any extent in proportion to the strength of the machine & battery. To render the spark effectual, a small quantity of fulminating silver and fine grained gun powder should be introduced between the points of the wire conductor, which should be left with about the eighth of an inch space between them for this purpose in the piece of baked wood. This composition should consist of about the eighth part fulminating Silver & the remaining seven eighths of gun powder, to introduce it conveniently, a hole should be made on either side of the baked wood above mentioned opposite to those on which the conductors enter, & by means of a quick scraped thin fire about the points of the conductors, these fixtures being completed they are situated in the hole in the rock, mineral, or clay, as above determined & the lowest covered with gun powder to a proper height. Dry sand is to be used for tamping between the charges or the parts of the charge, & when that nearest the surface is completed with powder, a wooden plug of a conical form is driven in and sand packed in to fill the hole.

The tamping should be removed with an ordinary pickax when all are completed in this manner, conductors covered with coarse twine a pressure there in good order are made to connect the conductors in the holes with each other which completes the fixture. The positive conductor is then brought in contact with the battery & the operation is completed by a general and simultaneous explosion.
